UNITED STATES PATENT OFFICE

94,614

DESIGN FOR A HOT TAMALE STEAMER OR SIMILAR ARTICLE

Charles W. Mabey, Indianapolis, Ind.

Application December 12, 1934, Serial No. 54,396

Term of patent 7 years

To all whom it may concern:

Be it known that Charles W. Mabey, a citizen of the United States, residing at Indianapolis, in the county of Marion and State of Indiana, has invented a new, original, and ornamental Design for a Hot Tamale Steamer or Similar Article of which the following is a specification, reference being had to the accompanying drawing, forming a part thereof:

Fig. 1 is a side elevational view of a hot tamale steamer, showing my new design, and Fig. 2 is a front view in perspective.

I claim:

The ornamental design for a hot tamale steamer or similar article, as shown.

CHARLES W. MABEY.
